DECORATIVE ELECTRIC LAMP BULB

Hideji Yamada, Tokyo, Japan, assignor to Riken Shinku
Kogyo Kabushiki Kaisha, Tokyo, Japan

Filed Jan. 2, 1973, Ser. No. 320,509

Claims priority, application Japan Aug. 30, 1972

Term of patent 14 years

Int. Cl. D26—04

U.S. Cl. D26—8

Fig. 1

Fig. 2

Fig. 3

Fig. 4

FIG. 1 is a front elevational view of a decorative electric lamp bulb embodying my new design;

FIG. 2 is a rear elevational view thereof;

FIG. 3 is a bottom view thereof;

FIG. 4 is a top view thereof.

The left and right side elevational views are substantially identical to the front and rear elevational views.

I claim:

The ornamental design for a decorative electric lamp bulb, as shown and described.
